(57) CLAIM

The ornamental design for a sandwich holder, as shown and described.

DESCRIPTION

FIG. 1 is a perspective view of a sandwich holder showing our new design; and

FIG. 2 is a top plan view of the sandwich holder in its unfolded paperboard blank form; and,

FIG. 3 is a perspective view of the sandwich holder of FIG. 1 wherein broken lines showing of a sandwich and grasping hand are for contextual illustrative purposes and form no part of the claimed design.

The dashed lines represent fold and tear lines in FIGS. 1 and 2.
